UNITED STATES PATENT OFFICE.

OLE GUNDERSON, OF SCHENECTADY, NEW YORK.

AEROPLANE.

1,362,292.

Specification of Letters Patent. Patented Dec. 14, 1920.

Application filed March 23, 1920. Serial No. 368,005.

To all whom it may concern:

Be it known that I, OLE GUNDERSON, a citizen of the United States, residing at Schenectady, in the county of Schenectady, 5 State of New York, have invented certain new and useful Improvements in Aeroplanes; and I do hereby declare the following to be a full, clear, and exact description of the invention, such as will enable others 10 skilled in the art to which it appertains to make and use the same.

This invention relates to aeronautics, and more especially to launching and landing devices; and the object of the same is primarily to construct a flying machine which 15 is designed and intended to rise along a substantially vertical line under the impulses of its own propellers.

In carrying out this object, one feature 20 of the invention is the arrangement of its supporting chassis.

Another feature is the special seat for the driver.

Another feature is the special anchor. 25 Details of the invention as applied to any ordinary biplane are set forth below and shown in the drawings wherein:

Figure 1 is a side elevation of the machine about to ascend.

30 Fig. 2 is a plan view of the machine in flight, the planes being dotted only.

The body of the machine is broadly designated by the letter B, P are the planes, T the tails controlled by a steering device or stick 35 S, and E the motor or engine controlled by a lever L; and no novelty is claimed for the parts mentioned.

The driving mechanism in the present case consists of a relatively small propeller 40 1 having two blades and mounted on a shaft 2 which rotates in a bearing 3, and a relatively large two-bladed propeller 4 mounted on a sleeve 5 surrounding the shaft 2 and in its own bearing 6, this propeller having its 45 blades pitched and therefore as a whole rotating oppositely to the other and in a plane a little distance from it. Power is communicated from the motor or engine E to the shaft and sleeve in any suitable manner, 50 as for instance by the bevel gearing broadly indicated at 7 in Fig. 1.

The drawings show the elements L and S for controlling the engine and for steering, and these elements will stand within reach 55 of an operator mounted on his seat. The latter in this case is specially constructed,

having a bottom 10 and a back 11 at about right angles to it, and both being rather narrow as shown in Fig. 2, the seat being mounted on standards or supports 12 which hold it rigid with the body no matter what position the latter assumes. Ordinarily the driver will sit on the seat bottom 10, but when ascending or starting along a practically vertical line he will slide back and sit on the seatback 11 as indicated in Fig. 1, and the bottom should be rather narrow so that his legs can pass astride it at this time. The harness for holding him in place will be constructed with a view to permitting him to shift his position as thus suggested.

The launching and landing devices employed in connection with the machine as thus described are specially constructed in order that the body B will stand almost vertical when the base of the chassis rests on the ground. Said chassis is herein shown as having a pair of front legs 20 leading downward and rearward from the body B and diverging from each other, and a single rear leg 21 leading back from the body to a point beyond the tails, or at least to such point that it will hold the tails off the ground; and 22 designates truss rods for bracing the legs. This chassis may have 25 for its base any suitable supports such as skids, shoes, pontoons, or wheels 23 and 24 as shown; but it is important that, whatever the form taken by the supports, the base of the chassis shall stand nearly at right angles to the length of the body. Therefore 30 when said base (the wheels as shown) rests on the ground, the body B stands upright on the ground G, and by preference inclined forward a little from a strictly vertical line. 35

In connection with this structure I preferably make use of an anchor, herein shown as composed of a rope 25 connected with some part of the chassis and hanging therefrom, and a spring clip 26 carried by the 40 rope and adapted to be engaged with some fixed object such as the stump 27 herein illustrated, although of course any heavy object such as a stone or perhaps an attendant would answer. The purpose of the anchor is to hold the machine upright on its base ready to start, and the spring clip will 45 slip off the object 27 (or be released by the attendant) when the start is made.

In launching a machine as thus constructed, it is stood on the base of its chassis as seen in Fig. 1 and anchored if an anchor

is used. The operator now climbs to his seat and assumes about the position shown, sitting on the seat-back 11 which at this time is nearly horizontal. The motor is 5 started and sped up, and eventually the propellers attain sufficient speed to lift the machine off the earth. As soon as clip 26 pulls off the object 27, the retarding effect of the anchor no longer prevails, and the aeroplane 10 rises along a substantially vertical line up which it is pulled by the combined action of the two propellers. When the desired altitude has been attained, the operator through his controls puts the machine on an 15 even keel and continues his flight as usual. When a landing is to be made, the machine is steered to a point near the surface and then its nose turned upward, the speed of the propellers is retarded and the momentum 20 of the machine soon ceases, and then by proper control the operator can permit the machine to settle tail-first until he lands on the base of the chassis with the nose of the machine in the air and again in the position 25 occupied at starting. In other words, launching is effected by use of a chassis which holds the machine with its nose upward, and employment of the motor and propellers; and landing is effected by a tail 30 drive, while descent is retarded and controlled by the same propellers. It is obvious that the wheels 23 and 24 might be replaced by other forms of shoes, and even pontoons could be used at the base of the chassis 35 so that the machine could rise from and alight upon the water.

What is claimed as new is:

1. In an aeroplane, a launching and landing chassis carried by the body with its 40 base substantially at right angles to the length of such body, and anchoring mechanism adapted to make frictional engagement with some fixed object.

2. The combination with an aeroplane including a body and tails; of a chassis including a rear leg projecting from the body beyond the tails, fixed front legs, and supports on said legs producing a base for the chassis standing in a plane substantially at 50 right angles to the length of the body.

3. The combination with an aeroplane including a body and tails; of a chassis including a rear leg projecting from the body beyond the tails, front legs projecting obliquely downward and rearward from the 55 front of the body and diverging from each

other, braces for these legs, and wheels at the lower ends of all legs standing in a plane substantially at right angles to the length of the body.

4. The combination with an aeroplane including a body and tails; of a launching chassis including legs projecting obliquely from the front of the body, and beyond the tails from the rear of the body, and wheels on said legs in a plane substantially at right angles to the length of the body, and anchoring mechanism including a spring clip suspended from said chassis and adapted to make frictional engagement with some fixed object. 60 65 70

5. In an aeroplane, the combination with a body and its tails and driving mechanism, the controls, and a seat fixedly supported from the body adjacent the controls and including a narrow bottom and a back at right angles thereto; of a launching chassis carried by the body and with its base in a plane across the rear of the tails substantially at right angles to the length of the body. 75 80

6. In an aeroplane, the combination with a body and its tails and driving mechanism, the controls, and a seat fixedly supported from the body adjacent the controls and including a narrow bottom and a back at right angles thereto; of a launching chassis carried by the body for holding the latter substantially vertical with its tails above the surface, and anchoring mechanism including a rope connected with the body and a spring clip carried by the rope and adapted to engage a fixed object. 85 90

7. The combination with an aeroplane including a body and tails; of a chassis including a rear leg projecting from the body beyond the tails, front legs projecting obliquely rearward from the front of the body and diverging from each other, braces for the legs holding their lower ends in a plane substantially at right angles to the length of the body, and anchoring mechanism including a rope connected with the braces and means on said rope adapted to make frictional engagement with some fixed object. 95 100 105

In testimony whereof I affix my signature in the presence of two witnesses.

OLE GUNDERSON.
